UNITED STATES PATENT OFFICE.

GEORGE SIMSON, OF THE BRITISH NAVY, ASSIGNOR OF ONE-HALF TO SIR W. G. ARMSTRONG, WHITWORTH AND COMPANY, LIMITED, OF NEWCASTLE-UPON-TYNE, ENGLAND.

GUN-MOUNTING.

1,305,839.

Specification of Letters Patent. Patented June 3, 1919.

Application filed September 21, 1917. Serial No. 192,538.

To all whom it may concern:

Be it known that I, GEORGE SIMSON, a subject of the King of Great Britain, engineer lieutenant in His Britannic Majesty's ship *Lord Clive*, have invented a new and useful Improvement in Gun-Mountings, of which the following is a specification.

This mounting is designed to enable a submarine or other similar craft to man her gun or guns while under water and to bring the same into action the instant she comes to the surface, or even when partially submerged. Should she require to dive hurriedly she may do so without the delay at present needed for stowing guns, getting the crew below, closing hatches, etc.

My invention is illustrated in the accompanying drawings in which Figure 1 is a longitudinal section through the gun cradle, 20 trunnion block and casing. Fig. 2 is a cross-section through the axis of the trunnions. Fig. 3 is a side elevation of the gun and mounting with the gun house and trunk shown in section. Fig. 4 is a rear elevation 25 of the gun and mounting with the gun house and part of the trunk shown in section.

A is a cylindrical block which is slightly tapered transversely and has in it a diametral hole in which is secured the cradle B. 30 A nut C holds the block hard up against a washer D fitting against a collar on the cradle so as to prevent water entering the mounting through the joint between the block and cradle. The front of the cradle 35 is fitted with a gland E packed with leather F to prevent water entering the mounting between the gun and cradle. The block A is fitted into a casing G having covers H bolted on at either side. In the casing G are slots 40 through which the gun and cradle project; each of these slots is made long enough to allow for the elevation and depression of the gun and cradle. Around the front slot is a recess into which is fitted a continuous 45 packing J which is kept in place by retaining pieces K: this forms a water tight joint between the block and casing. A spigot L is formed on the base of the casing for bolting it to the pedestal M, in the rear of 50 which is cut a slot to allow of the movement of the gun and cradle to a high angle of elevation.

Fitting around the front slot of the casing

G is a bracket N which connects the casing to the gun house O. P is a trunk extending down into the interior of the vessel and having secured to it at its upper end a circular casting Q which is bolted to the pedestal M and also to the gun house O. Near the base of the trunk is a manhole with a water tight door R through which the crew can pass into the trunk and so by means of a ladder S into the pedestal and gun house. A platform T is constructed in the gun house at a suitable height for working the mounting. The trunk revolves in a packed gland U fitted to the outer shell of the vessel and packed with leathers V thus preventing water entering the vessel around the outside of the trunk.

At a convenient height the trunk P is surrounded by a training rack W which is secured to the structure of the vessel and into which meshes a pinion X carried in a bracket Y and actuated by a vertical shaft Z which is geared to a handwheel A¹ mounted on the pedestal M. The trunk, mounting and gun house are supported on rollers B¹, the upper roller path C¹ being secured to a casting D¹ fitted around the bottom of the trunk, while the lower roller path E¹ is secured to the main structure of the vessel.

The ammunition is raised from the bottom of the trunk by means of a hoist cage F¹ from which it is transferred to a chute G¹ under the working platform T. The gun is elevated by means of a rack H¹ secured to the cradle and meshing with a pinion J¹ which is geared to a handwheel K¹. The sights L¹ for the gunlayer and trainer are 90 of the periscope pattern leading out through the sides of the gun house, glands M¹ being fitted to prevent entry of water. Seats N¹ are provided for the gunlayer and trainer.

What I claim is:

1. In a gun mounting, the combination of a cylindrical block capable of partial rotation about its own axis, a casing fitting watertight around the block, a cradle fixed in a diametral hole in the block and means for rotating the block within the casing.
2. In a gun mounting, the combination of a cylindrical block capable of partial rotation about its own axis, a cradle fixed in a diametral hole in the block, a casing fitting watertight around the block and slotted to

allow for elevation and depression of the cradle and means for rotating the block within the casing.

3. In a gun mounting, the combination of a cylindrical block, a casing fitting watertight around the block, a cradle fixed to a diametral hole in the block, a cover secured to each side of the casing and means for rotating the block within the casing.
- 10 4. In a gun mounting, the combination of a pedestal, a casing secured to the top thereof, a cylindrical block fitting watertight within the casing, a cradle fixed in a diametral hole in the block and means for rotating the block within the casing.
- 15 5. In a gun mounting, the combination of a pedestal, a casing secured to the top thereof, a cylindrical block fitting watertight within the casing, a cradle fixed in a diam-

etral hole in the block, means for rotating the block within the casing and means for rotating the pedestal.

6. The combination of a gun house, a trunk depending therefrom, a casing within the gun house, a cylindrical block capable of partial rotation about its own axis and fitting watertight within the casing, a cradle fixed in a diametral hole in the block, means for rotating the gun house and trunk and means for rotating the block within the casing.

In testimony that I claim the foregoing as my invention, I have signed my name this fourth day of June 1917.

GEORGE SIMSON.
